United States Patent Office

Des. 184,715
Patented Mar. 31, 1959

184,715

PITCHER

Richard T. Cornelius, Minneapolis, and Nelson F. Cornelius, Anoka, Minn.

Application October 8, 1956, Serial No. 43,266

Term of patent 14 years

(Cl. D44—21)

FIG. 1

FIG. 3

Fig. 1 is a perspective view of a pitcher showing our new design with the cover closed and viewed from the obverse side thereof.

Fig. 2 is a perspective view, similar to Fig. 1, showing the cover opened and viewed from the reverse side.

Fig. 3 is a perspective view of the pitcher viewed from the top thereof and showing the cover opened.

We claim:

The ornamental design for a pitcher, as shown.
